Primary Examiner — Patricia A Palasik(74) *Attorney, Agent, or Firm* — Hodgson Russ LLP(57) **CLAIM**

The ornamental design for a welding cap, as shown and described.

DESCRIPTION

FIG. 1 is a perspective view of a first embodiment of a welding cap, showing our new design;
 FIG. 2 is a front elevation view thereof;
 FIG. 3 is a rear elevation view thereof;
 FIG. 4 is a left side elevation view thereof;
 FIG. 5 is a right side elevation view thereof;
 FIG. 6 is a top plan view thereof;
 FIG. 7 is a bottom plan view thereof;
 FIG. 8 is a cross-sectional view thereof, taken along 8-8 of FIG. 2;

FIG. 9 is a perspective view of a first embodiment of a welding cap, showing our new design;
 FIG. 10 is a front elevation view thereof;
 FIG. 11 is a rear elevation view thereof;
 FIG. 12 is a left side elevation view thereof;
 FIG. 13 is a right side elevation view thereof;
 FIG. 14 is a top plan view thereof;
 FIG. 15 is a bottom plan view thereof; and,
 FIG. 16 is a cross-sectional view thereof, taken along 8-8 of FIG. 10.

The broken lines in the figures illustrate portions of the welding cap that form no part of the claimed design.
